UNITED STATES PATENT OFFICE.

CHARLES H. MORTIMER, OF CHICAGO, ILLINOIS, ASSIGNOR OF ONE-HALF TO CHARLES P. SOULÉ, OF CHICAGO, ILLINOIS.

METHOD AND MEANS FOR TREATING PAPER ON A PRINTING-PRESS.

1,037,965.

Specification of Letters Patent. Patented Sept. 10, 1912.

Application filed January 27, 1911. Serial No. 604,944.

To all whom it may concern:

Be it known that I, CHARLES H. MORTIMER, a citizen of the United States, residing at Chicago, in the county of Cook and State of Illinois, have invented new and useful Improvements in Methods and Means for Treating Paper on a Printing-Press, of which the following is a specification:

The presence of electricity under certain conditions of temperature in paper being fed to printing presses has long been the cause of great trouble and expense to printers because the electricity not only affects the character of the work but it reduces the speed, and slip-sheeting or smutting is made necessary by reason of the offsetting which almost invariably occurs.

The object of this invention is to eliminate the electricity from the sheet and to shrink the sheet before it is printed by applying heat to the sheet while on the feed board of a printing press, and to prevent offsetting by applying heat to the sheet after it is printed and while it still remains on the impression cylinder.

In the accompanying drawings illustrating one embodiment of the invention Figure 1 is a sectional view. Fig. 2 is a top plan view of the feed board of a printing press showing the invention embodied therewith. Fig. 3 is a bottom plan view of a portion of the feed board showing the invention. Fig. 4 is an enlarged sectional view showing a slightly different embodiment of the invention. Fig. 5 is a fragmentary bottom plan view of the perforated plate. Fig. 6 is a detail view, partly in section, showing one end of the heat coil and the manner of supporting it. Fig. 7 is a detail sectional view showing the means for adjusting the damper plate. Fig. 8 is a sectional view on the line 8-8 of Fig. 7.

My invention may be embodied with printing presses of various types and in the drawings I have shown the feed board 9 and the impression cylinder 10 conventionally. The feed board has a transverse opening 11 extending across that portion of the feed board over which the paper travels. This opening is provided with a perforated cover plate 12 which is fastened to the feed

board and a perforated damper plate 13 is fastened to the underside of the cover plate by screws 14 which pass through slots 15 in the damper plate and enter the cover plate (Fig. 5). The perforations in the damper plate are adapted to be registered or shifted out of registration with the perforations in the cover plate by adjusting the damper plate longitudinally and this adjustment is accomplished by operating the slide bar 16 which is connected with the damper plate at one end thereof and projects laterally under the feed board in suitable guides 17 thereon. By operating this slide bar the damper plate may be shifted longitudinally as desired and in this movement the damper plate is guided between the side walls 11' of the opening 11. The damper plate may be shifted to regulate and control the heat as desired.

An electric heat coil 18 of suitable construction is supported on the underside of the feed board below the opening 11 and is protected by a shield 19 which is preferably hinged to the feed board at 20 and secured in place by suitable fastening devices 21. The heat coil is preferably provided with tubular sockets 22 in its ends to receive the plugs 23 which are made rigid with the angle supporting arms 24 and these arms are engaged with brackets 25 on the underside of the feed board at the ends of the opening therein. This manner of supporting the heat coil provides for such expansion and contraction as may take place during the use and non-use of the invention without necessitating any special adjustment or attention.

The heat coil is located in the angle formed between the feed board and the impression cylinder, and the shield 19 is provided with openings 26 in its bottom, as shown in Figs. 1 and 3, so that some of the heat from the coil may be transmitted to the cylinder. The shield may have openings 27 in its front and back, in addition to the bottom openings 26, as shown in Fig. 4, if desired. One or more lines of openings 28 may also be provided in the feed board in front of the transverse opening 11.

In practice, when conditions require it,

the switch 29 is operated to energize the heat coil and the damper plate is adjusted to register its perforations with the perforations in the cover plate so that the heat from 5 the coil may pass up to heat the paper and absorb the electricity therein. Some heat will pass through the shield and upward through the openings 28 and some will pass to the cylinder, further heating the sheet 10 on the cylinder after it is printed. The heat which is applied to the sheet while on the feed board not only eliminates the electricity in the paper but also shrinks the paper before it is printed. By thus shrinking 15 the paper before it is printed the proper registration of the work in successive printing operations is insured. The sheet is further heated after it is printed and while still remaining on the impression cylinder and 20 this prevents offsetting.

My invention is simple in character, inexpensive to manufacture and applicable to a large variety of presses. It entirely eliminates the electricity in the paper and avoids 25 the consequences due to its presence, preserving the character of the work and speed of the press. Furthermore, it obviates the necessity of slip-sheeting or smutting by reason of the heat imparted to the sheet 30 while on the feed-board and on the cylinder and in this way eliminates an expense which has heretofore been necessary. The invention has other advantages which will be apparent to those skilled in the art and 35 of course it will be understood that the heat coil may be heated by gas or otherwise instead of electrically if desired.

What I claim and desire to secure by Letters Patent is:

40 1. The herein-described method which consists in applying heat to one face of the sheet to be printed and before the printing operation to eliminate electricity from the sheet and to shrink the sheet before it is 45 printed, and subsequently applying heat to the opposite face of the sheet after the printing operation to prevent off-setting.

2. The herein described method which 50 consists in preserving the character of the work and speed of the press and preparing the sheet for proper registration in successive printing operations by applying heat to one face of the sheet while on the feed-board of a printing press to eliminate electricity from and to shrink the sheet before it is printed, and also applying heat to the 55 opposite face of the sheet after it is printed and while still remaining on the impression cylinder to prevent offsetting.

60 3. The combination of the impression cylinder of a printing press, a feed board provided with perforations adjacent its delivery end, and heating means located in the angle between said cylinder and feed board

beneath said perforations in the board 65 whereby heat may be delivered from said means to the sheet on the board before the printing operation and to the sheet on the cylinder after the printing operation.

4. The combination of the impression cylinder of a printing press, a feed board provided with perforations adjacent the cylinder end, and means located beneath the feed board and adjacent the cylinder for applying heat to one face of the paper before the 75 printing operation and to the opposite face after the printing operation.

5. The combination of a feed board for a printing press having a transverse opening therein, a perforated cover plate over 80 said opening and forming a part of the feed-board, a heating device located below the cover plate and having sockets in its ends, plugs loosely arranged in said sockets, and supports engaged with said plugs and 85 the feed board to suspend the heating device from the board and permit expansion and contraction of said device, substantially as described.

6. The combination of a feed board for 90 a printing press having a transverse opening therein, perforated cover and damper plates arranged in juxtaposition over said opening, the cover plate forming a part of the feed-board, means for adjusting the 95 damper plate, a heating device located below said plates and having tubular guides in its ends, plugs loosely arranged in said sockets, and angle arms rigid with said plugs and engaged with said feed board to 100 suspend the heating device from the feed board and permit expansion and contraction of said device, substantially as described.

7. The combination of a feed board for 105 a printing press having an opening therein, a perforated cover plate over said opening and forming a part of the feed-board, a heating device located below said cover plate, and a perforated shield supported 110 from the underside of the feed board and covering said heating device, substantially as described.

8. The combination of the feed board and impression cylinder of a printing press, a 115 heating device suspended from the underside of the feed board in the angle formed by said board and the cylinder and adjacent to the delivery end of the board and to the cylinder, said board having a transverse 120 opening therein over the heating device, perforated cover and damper plates arranged in juxtaposition over said opening, the cover plate forming a part of the feed-board, and means for adjusting the damper 125 plate.

9. The combination of the feed board and impression cylinder of a printing press, a

heating device arranged in the angle formed by the feed board and the cylinder and adjacent to the delivery end of the feed board and to the cylinder, said feed board having

5 an opening over said heating device, a perforated cover plate over said opening and forming a part of the feed-board, and a

perforated shield supported from the underside of the feed board and inclosing the heating device.
